(57) **CLAIM**

The ornamental design for a retaining ring and back nut for electric cable connector as shown and described.

DESCRIPTION

FIG. 1 - Top, front, left side perspective view;

FIG. 2 - Bottom, rear, right side perspective view;

FIG. 3 - Front elevation view, the rear elevation view being a mirror image;

FIG. 4 - Left-side elevation view, the right-side elevation view being a mirror image;

FIG. 5 - Top plan view;

FIG. 6 - Bottom plan view;

FIG. 7 - Cross-section view taken along line 7-7 of FIG. 5; and,

FIG. 8 - Exploded perspective view of the device of FIG. 1. The broken lines in the drawing depict portions of the retaining ring and back nut for electric cable connector that form no part of the claimed design.

1 Claim, 4 Drawing Sheets
